DEEP WELL PUMPING MECHANISM

Filed Sept. 24, 1932 2 Sheets-Sheet 2

UNITED STATES PATENT OFFICE

JOHN H. YOUNG, OF WARREN, PENNSYLVANIA

DEEP WELL PUMPING MECHANISM

Application filed September 24, 1932. Serial No. 634,753.

This invention relates to mechanism which is especially adapted for pumping, and more especially to such mechanism which is designed for pumping deep oil wells.

5 An object of the invention is to provide well pumping mechanism of such design as to be capable of withstanding the great strains imposed upon pumping apparatus when used in connection with oil wells of great depth, 10 and in order to relieve excessive strains on the pump rod.

Another object of the invention is to counterbalance the excessive weight of pump rods of great length when used in pumping 15 oil wells, and of the liquid in the well tubing which is considerable in oil wells which under present methods sometimes are several thousand feet in depth.

Another object of the invention is to equalize the power required in both the up and down strokes of pumps of the character referred to so that such power may be applied smoothly, thus avoiding unnecessary shocks and jars upon the pumping mechanism, and 25 hence lessening the danger of the breakage of the pump rods due to such sudden jars and vibrations.

Another object of the invention is to reduce the cost of pumping equipment to a minimum 30 by providing such equipment with the aforesaid shock reducing and power distributing means which, under the present invention, contains a minimum number of parts to accomplish the objects aforesaid.

35 A further object of the invention is to reduce the weight of the pumping equipment to a minimum consistent with the necessary strength and disposition of the parts to resist 40 all strains imposed upon the operating mechanism during its normal operation.

With the above and other important and valuable objects in view the invention consists in the construction and arrangement of 45 parts as hereinafter described, certain embodiments of the invention being illustrated in the accompanying drawings, in which:—

Fig. 1 shows in elevation certain parts of 50 a pumping apparatus for deep well pumps embodying the invention;

Fig. 2 is an elevation at right angles to that shown in Fig. 1;

Fig. 3 illustrates in elevation a slightly modified form, and

Fig. 4 is a similar view illustrating still a 55 different modification.

Referring first to Figs. 1 and 2, the well curbing is provided with any suitable foundation or support, 1, 2, in which the members 1 may be of concrete or heavy timbers and supported thereon and secured thereto are the timbers or slabs 2, preferably arranged in rectangular form to enclose the well tubing 4 whose upper end portion may be provided with the usual stuffing box 5, through which and said tubing passes the pump rod 6.

Securely anchored in the foundation, 1, 2, and as herein shown arranged in parallelism upon opposite sides of the pump barrel, are guide rods 8, 8, the upper ends of these rods being threaded and passing through apertures in a plate 7, nuts 9 being run upon the threaded upper ends of the guide rods for securing thereto the plate 7. The plate 7, as will be seen, forms a rigid connection between the upper ends of the guide rods which rods are thereby held fixedly in spaced relation, and braced so as to form with the foundation, a rigid structure. This is quite important as the guide rods 8 are subjected to 50 severe lateral strains during the operation of the pumping mechanism, as will more clearly appear hereinafter.

The pump rod 6 is extended upwardly 55 through the plate 7, and a tubular guiding sleeve 10 receives the upper portion of the rod, said sleeve being provided at its upper end with a flange 10a between which flange and the upper surface of the plate 7 a heavy spiral spring 11 is confined. The lower portion of the sleeve 10 passes through a central guiding aperture in the plate 7, which is of a size to receive the sleeve, and permit its free movement therethrough. The upper face of the flange 10a abuts against a lock nut 42 which is provided with a set screw 43 for securing the lock nut rigidly to the rod 6. By this construction the spring 11 is confined between the plate 7 and flange, and exerts an upward thrust to the pump rod. 100

A yoke 12, provided with holes therethrough which receive the guide rods, is thus mounted for reciprocating movements on said rods, the yoke having a central aperture 5 through which passes the pump rod 6, which latter is rigidly secured to and confined to reciprocating movements with the yoke by two lock nuts 13, 14, in engagement respectively, with the lower and upper faces of the 10 yoke 12, and held to the pump rod by set screws 13a, 14a. Extending outwardly from opposite ends of the yoke 12, and in alignment with each other, are spindles 15, which are journaled in tubular bearings 16 carried at 15 the upper ends of the pitmen 17. The lower ends of the pitmen are similarly provided with tubular bearing members 18 journaled upon crank pins 19 which project from the large gear wheels 20. The gears 20 are rigidly secured to a shaft 21, supported for rotation in bearings carried rigidly by the foundation timbers. The gears 20 mesh with pinions 22, rigidly keyed to a shaft 23, mounted also in bearings which are supported by 25 the same timbers of the foundation as the bearings which support the shaft 21. The shaft 23 is extended to one side of the foundation and carries a pulley wheel 24 which receives power from a suitable source through 30 the driving belt 25.

With the parts as above described, when power is applied, through the drive belt 25, pulley 24, shaft 23, and pinions to the large gears 20, rotation of the latter will, through 35 the pitman, cause reciprocation of the yoke 12, and of the pump rod 6, to which latter the usual pump plunger or piston is connected. Referring to Fig. 2, a rotation of the gears 20 in a contra-clockwise direction as seen in this 40 view, will cause a downward movement of the pump rod, thereby causing the tubular spring guide 10 to descend through the guiding aperture in the plate 7, the flange 10a by such movement compressing the heavy spiral 45 spring 11, and thus storing power in the spring to be subsequently applied in lifting the load, which consists of the weight of the plunger rod, plunger, and liquid in the well. The downward movement thus described is 50 about to begin when the parts occupy the positions shown in Fig. 2, with the gears 20 moving in the direction indicated by the arrow, so that when the down stroke of the pump rod is taking place the major portion 55 of such stroke is made during the time that the pitmen 17 are more nearly in line with the guide rods and the pump rod, thereby effectively applying the power received from the belt 25, in storing up that power in the spring. 60 The weight of the liquid in the well and of the pump parts, consisting of the rod and plunger, is added to the power received from the belt in compressing the spring. After the crank pins on the gears 20 have traversed approximately 180° in making the down

stroke, the movement of the crank pins from this point upward is applied to effect the lifting or working stroke, in which the power of the spring 11 is largely instrumental. The parts are so proportioned and arranged that the spring 11 acts essentially as a counterbalance as its force is exerted in opposition to the load which must be overcome in the up-strokes of the pump. In the application of power to the yoke or cross bar 12, to cause the pump rod to descend, during which the spring 11 is compressed, the strain imposed upon the parts is such that to effectually resist the same it is necessary to provide a rigid frame-work, and this has been found in practice to be ample with the arrangement of guide rods 8 when the latter are firmly anchored in the foundation timbers 1, 2, at their lower ends, with the upper ends thereof secured together by a plate or bridge 7, and such arrangement is employed in connection with the yoke 12, having at opposite ends thereof the connections 17 with the crank pins 19 on the large gears. This particular arrangement serves to minimize the lateral strains which are applied to the pump rod through the spaced gear wheels 20 and pinions 22, together with the tubular spring guide which insures a straight line movement of the upper portion of the pump rod during the compression of the spring, which latter would have a tendency to bind or to bend the pump rod except for the guiding function of the tubular member.

The arrangement of the several parts as shown and described is such that all of said parts contribute to the several benefits and advantages of the pumping mechanism, whereby the same is very effectively operable in situations where these pumps are applied to wells of excessive depth.

In the embodiment of the invention illustrated in Fig. 3, I have provided three spiral springs 31, in lieu of the single spring as shown in Figs. 1 and 2, the other parts which are associated with the springs being slightly modified conformably with the addition of the two extra springs. In this construction, the pump rod 6 extends upward, through and beyond the yoke 12, through a hole in a flange or plate 32 which may have suitable bracing cables 34 extending downwardly therefrom to the foundation to steady the structure. The guide rods 8, threaded at their upper ends, pass through apertures in the plate 32 on opposite sides of the pump rod 6 and are secured to the plate by nuts 35. The rod 6 is provided with a lock nut 42 which acts as an abutment for a plate 36 under the stress of the three spiral springs 31, the central one of which surrounds the tubular spring guide 10. The lower end of this guide is arranged to pass freely through a circular aperture in a flange or plate 38. The plate 38 is provided with holes on opposite

- sides of the central aperture which receives the tubular guide 10, through which pass the guide rods 8, and the plate 38 is supported upon the guide rods by lock nuts 40. Tubular spring guide sleeves 41, 41, extend between the plate 36 and the plate 38, and the spiral springs 31, surround the tubular guides 10, 41, the plate 36 being provided with apertures 39 which permit it to slide freely over the tubular guides 41 when the pump rod is caused to move downwardly under the power transmitted thereto through the yoke 12. Power is applied to this yoke to reciprocate the pump rod through the pitmen 17, gears 20, and pinions 22, which latter are carried by the shaft 23, having thereon the pulley 24, which receives power from a suitable source, through the belt 25, as in the construction shown in Figs. 1 and 2.
- Upon the downward movement of the pump rod 6 in the construction now being described, the plate 36 is caused to descend, carrying with it the central tubular guide 10, but sliding freely over the tubular guides 41, such downward movement effecting the compression of the three springs, thus storing up power for use on the working or upward stroke of the pump, as in the construction first described. In the modification illustrated in Fig. 3, the use of three springs, instead of a single spring, is for the purpose of affording additional spring power for use in wells of such depth that the load to be lifted is too great for a single spring, and where the three springs are employed, as will be obvious, a greater amount of power from the prime source of power, is necessary. In the modified form it will be seen that the guiding function, and the steadyng function of the parts are effectively secured by the arrangement of the three tubular spring guides in connection with the plate 36, which, being caused to travel in a right line as it moves downward to compress the springs, will not be permitted to tilt, or move out of line. This result is insured by the three tubular guiding members, the central one, 10, of which reciprocates through a hole in the plate 38, while the tubular members 41 cooperate in the guiding function of the plate 36 as the latter reciprocates over the tubular members 41 in the downward movement of the plate during the compression of the springs.
- In Fig. 4 still a different modification is illustrated. In this construction, where a single compression spring is utilized, the yoke 12 is provided near its opposite ends with sleeves 44, which guide the yoke truly in its reciprocating movements on the guide rods 8, and the heavy spiral spring 45 encircles the pump rod 6, and is confined between a plate 5a of the stuffing box 5, on which the spring rests, and a washer 50 at the upper end of the spring, said washer
- bearing against the lock nut 13. As in the construction illustrated in Figs. 1 and 2, the yoke 12 is confined between the lock nuts 13, 14, which are secured immovably by set screws to the pump rod 6. Further description of the construction shown in this view of the drawings is believed to be unnecessary, as the operation of the parts is the same as that in the form of the invention illustrated in Figs. 1 and 2, the difference between the present modification, and that shown in Figs. 1 and 2 being mainly in the arrangement of the counterbalancing spring below the yoke, instead of above the yoke, and in the consequent omission of the tubular guiding member within the spring.
- Other modifications of the invention may obviously be made than those above described, and it is to be understood that the invention is not confined to the particular construction and arrangement of the parts described, but may be varied provided such variations or additional modifications are within the scope of the following claims.
- I claim:—
1. In pumping apparatus of the class described, the combination with a pump barrel and a pump rod, of spaced parallel guide rods on opposite sides of the pump rod having their lower portions rigidly anchored in the foundation and their upper portions rigidly connected by a plate, a yoke mounted for reciprocation on said guide rods and directly connected with said pump rod, a tubular spring guide on said rod and constructed for reciprocating movements through an aperture in said plate, and a balancing spring surrounding said tubular spring guide and confined between said plate and an abutment on the pump rod.
  2. In a pumping apparatus the combination with a pump barrel and a pump rod therein, of spaced parallel guide rods rigidly anchored at their lower ends in the pump foundation, and having their upper end portions connected by a plate, a yoke mounted to reciprocate upon said guide rods and rigidly secured to said pump rod, a tubular spring guiding member secured to said pump rod and arranged to reciprocate through a guiding aperture in said plate, a spiral balancing spring surrounding said member and confined between an abutment on the pump rod, and said plate, and means including spaced gears, crank pins on said gears, and pitmen connecting said pins with opposite ends of said yoke to effect reciprocation of the pump rod and compression of said spring.
  3. In pumping apparatus the combination with a pump barrel and pump rod mounted to reciprocate therein, of spaced parallel guiding rods arranged on opposite sides of and in line with said pump rod, the lower portions of said guide rods being firmly anchored in the pump foundation, a rigid

plate connecting the upper portions of said guide rods and provided with a central aperture, a tubular spring guide surrounding said pump rod and arranged to reciprocate through said aperture, a spiral counterbalancing spring surrounding said tubular spring guide and confined between said plate and an abutment on the pump rod, a shaft mounted in bearings supported by the pump foundation, gears carried by said shaft and provided with cranks, pitmen connecting said cranks with the outer ends of said yoke, and means for driving said gears to effect reciprocation of the pump rod and compression of the balancing spring.

4. Pumping apparatus of the class described, comprising in combination, a pump barrel and a pump rod mounted for reciprocating movements in said barrel, guide rods spaced laterally upon opposite sides of said pump rod and in line therewith, said guide rods having their lower ends rigidly anchored in the pump foundation, a plate rigidly connecting the upper ends of said guide rods and provided with an aperture to receive and guide the upper portion of the pump rod, a movable plate below the first mentioned plate, a tubular spring guide surrounding the pump rod and connected with said movable plate, spring guiding tubular members upon opposite sides of said first mentioned tubular spring guiding member arranged to slide through apertures in said movable plate, spiral springs surrounding said tubular members and confined between said movable plate and an abutment member supported against movement on said guide rods and provided with a central guiding aperture to receive said first mentioned tubular spring guide member, a yoke slidable upon said guide rods and provided with an aperture to receive said pump rod, means for rigidly securing the pump rod to the yoke, and power operated means for reciprocating said yoke, pump rod, and movable plate to compress said springs during the downward movement of the pump rod.

5. In pumping apparatus of the class described, the combination with a pump barrel and pump rod mounted to reciprocate therein, of spaced guide rods arranged in line with and upon opposite sides of said pump rod and anchored at their lower ends in the pump foundation, a plate rigidly connecting the upper portions of said guide rods and provided with a central aperture to receive said pump rod, a movable plate connected to said pump rod and provided at its central portion with a downwardly extending tubular spring guide member and upon opposite sides thereof with apertures, spaced spring guide members supported upon opposite sides of said first named tubular spring guide member, an abutment plate located at the lower

end portions of said tubular guide members and provided with a central aperture to receive and guide said first mentioned tubular spring guide member, spiral balancing springs surrounding said spring guide members and confined between said movable plate and abutment plate, a yoke slidably mounted upon said guide rods and secured to said pump rod, and means for reciprocating said yoke including a shaft mounted in bearings on the pump foundation, pinions on said shaft, a second shaft mounted in bearings on the pump foundation, gears meshing with said pinions and supported by said shaft, cranks carried by said gears, and pitmen connecting said cranks with the outer end portions of said yoke.

6. Pumping apparatus of the class described comprising, in combination, a pump barrel, a pump rod mounted to reciprocate therein, guide rods located in line with and upon opposite sides of said pump rod and having their lower ends anchored firmly in the pump foundation, a plate rigidly connecting the upper end portions of said guide rods, a yoke reciprocating upon said guide rods, means for rigidly securing said yoke to said pump rod, a spiral balancing spring surrounding said pump rod and confined between an abutment below said yoke and a pump rod stuffing box member, and means for reciprocating said yoke comprising a shaft supported by bearings on the pump foundation and carrying pinions, a second shaft supported by bearings on said foundation and carrying spaced gears meshing with said pinions, crank pins carried by said gears, pitmen connecting said crank pins pivotally with the outer ends of said yoke, and power means for driving said pinions.

7. A pumping apparatus of the class described comprising, in combination, a pump barrel, a pump rod mounted to reciprocate therein, guide rods located in line with and upon opposite sides of said pump rod and having their lower ends anchored firmly in the pump foundation, a plate rigidly connecting the upper end portions of said guide rods and provided intermediate said guide rods with an opening to receive and guide the pump rod, a yoke reciprocating upon said guide rods and provided with an aperture intermediate said guide rods to receive the pump rod, means for rigidly securing said yoke to said pump rod, a heavy spiral balancing spring surrounding said pump rod and confined between an abutment on said pump rod and an unyielding member, said spring being arranged to be compressed upon downward movement of the yoke to counterbalance the weight of the pump plunger, and column of liquid in the well, and means for reciprocating said yoke, including a shaft supported by bearings on the pump foundation, pinions on said shaft, a

second shaft supported by bearings on said foundation, and carrying spaced gears meshing with said pinions, cranks supported by said gears, pitmen connecting said cranks 5 pivotally with the outer ends of said yoke, and power means for driving said pinion shaft.

8. A pumping apparatus of the class described comprising, in combination, a pump 10 barrel, a pump rod mounted to reciprocate therein, guide rods located in line with and upon opposite sides of said pump rod and having their lower ends anchored firmly in the pump foundation, a plate rigidly connecting the upper end portions of said guide rods and provided intermediate said guide rods with an opening to receive and guide the pump rod, a yoke reciprocating upon said guide rods and provided with an aperture intermediate said guide rods to receive the pump rod, means for rigidly securing 15 said yoke to said pump rod, a heavy spiral balancing spring surrounding said pump rod and confined thereon so as to be compressed 20 upon downward movement of the yoke to counterbalance the weight of the pump plunger and column of liquid in the well, and means for reciprocating said yoke, including a shaft supported by bearings on the 25 pump foundation, pinions on said shaft, a second shaft supported by bearings on said foundation, and carrying spaced gears meshing with said pinions, cranks supported by 30 said gears, pitmen connecting said cranks pivotally with the outer ends of said yoke, 35 and power means for driving said pinion shaft.

In testimony whereof I have hereunto set my hand this 17th day of September, A. D. 1932.

JOHN H. YOUNG.
